UNITED STATES PATENT OFFICE.

GEORGE ACKERMANN, OF CINCINNATI, OHIO, ASSIGNOR TO THE R. J. REYNOLDS TOBACCO COMPANY, OF WINSTON-SALEM, NORTH CAROLINA, A CORPORATION OF NEW JERSEY.

DESIGN FOR A CAN.

44,463.

Specification for Design.

Patented Aug. 12, 1913.

Application filed October 4, 1912. Serial No. 723,954. Term of patent 14 years.

To all whom it may concern:

Be it known that I, GEORGE ACKERMANN, a citizen of the United States of America, and resident of Cincinnati, county of Hamilton, and State of Ohio, have invented a certain new, original, and ornamental Design for Cans, of which the following is a specification.

The figure of the accompanying drawing is a perspective view of a can embodying my invention.

The body A of the can is cylindrical. Near the lower edge of the cylindrical body A is an enlarged rounded bead a , below which projects a comparatively small cylindrical collar a' . Near the top of the cylindrical body A is a small rounded bead a^2 .

At substantially the same distance from the bottom of the can that the bead a^2 is from the top of the cover, there is a small rounded bead a^3 in the body of the can. The cover of the can has a narrow cylindrical flange B, adjacent to the shoulder a^2 , a boss b, which is of greater width than rounded bead a and flares outward beyond the cylindrical body A, and a rounded top b'.

I claim:

The ornamental design for a can as shown and described.

GEORGE ACKERMANN.
